UNITED STATES PATENT OFFICE.

JOHN C. PERKINS, OF KALAMAZOO, MICHIGAN, ASSIGNOR TO GEORGE W. MILLER AND HORACE G. HAINES, BOTH OF SAME PLACE.

RAILWAY HAND-CAR.

SPECIFICATION forming part of Letters Patent No. 290,703, dated December 25, 1883.

Application filed October 25, 1883. (No model.)

To all whom it may concern:

Be it known that I, JOHN C. PERKINS, a citizen of the United States, residing at Kalamazoo, county of Kalamazoo, State of Michigan, have invented a new and useful Railway Hand-Car, of which the following is a specification.

My invention consists in certain improvements hereinafter described and claimed.

10 In the drawings forming a part of this specification, Figure 1 is a side elevation of the hand-car; Fig. 2, a top view of the same; and Fig. 3 is an elevation showing a brake device.

15 The frame F, rectangular in form, is provided with four running or traction wheels, two of which are shown in Figs. 1 and 3, located on a rail of the track. Two like wheels run on the opposite rail of the track, as in the common style of four-wheeled hand-cars. The 20 axles of these wheels are revoluble and said wheels rigidly secured at each end of said axles. The driving-gear B D is of a style commonly used, and will be readily understood by a reference to Fig. 1.

25 The frame for supporting the propelling-levers h h is an important and novel feature of my device. Said frame v v is made from hollow pipe in the form of a letter S, and supported above the frame F by four hollow stand-

30 ards, a a, one at each terminus and one at each bow of the S-frame. The propelling-levers consist of handles h h and double-truss bars e e. Said bars are securely held in a square parallel position to each other by brace- 35 rods r r, thus preventing the levers from twisting and causing any binding of the pivoted parts. The levers are located in the U portions of the S-frame v v, and pivotally connected with the bows of said frame at f f. At

40 each end of the axle of the gear B is connected a crank, e. These cranks radiate from said axle at different angles to each other, Fig.

1. The truss-levers are pivotally connected with said cranks e e by rods t t, Figs. 1 and 2. Said levers may be centrally fulcrumed and 45 rods t t pivotally connected with the ends, if preferred. Such a construction is light, simple, and occupies but a small portion of the space usually devoted to such parts, and the ease and speed in running the device are 50 greatly facilitated. The cranks e e are provided with extra adjusting-holes e', to control the sweep of the truss-levers. The brake in Fig. 3 consists of an S-shaped casting, b, terminating at each end in oppositely-angled 55 brake-shoes adapted to engage two wheels at one time by a single effort of the operator in stepping on the treadle A. Said treadle has a downwardly-extending spring-actuated pintle, said pintle being pivotally connected with 60 lever z. The other end of the lever z is secured to the brake-casting b, or to an axle with which said casting may be connected.

Having thus described my invention, what I claim as new is—

1. The combination, with the hollow S-shaped lever-frame having suitable supports, of the propelling-levers and running-gear of a hand-car, said parts being constructed and arranged substantially as set forth.

2. In a hand-car or other lever-propelled vehicle, the S-shaped lever-frame and supports, adapted for the purpose set forth.

3. The combination, with the S-shaped frame, of the double-bar-levers having the truss-braces 75 and the rods connecting said levers with the running-gear cranks.

In testimony of the foregoing I have hereunto subscribed my name in the presence of two witnesses.

JOHN C. PERKINS.

Witnesses:

ARTHUR CAMERON,
CHARLES O. JOHNSON.
